UNITED STATES PATENT OFFICE.

WILLIAM W. STEWART, OF BROOKLYN, NEW YORK.

HERMETICALLY-SEALED RECEPTACLE FOR FOOD-PRESERVATION.

SPECIFICATION forming part of Letters Patent No. 250,109, dated November 29, 1881.

Application filed April 16, 1881. (No model.)

To all whom it may concern:

Be it known that I, WILLIAM WASHINGTON STEWART, of Brooklyn, county of Kings, in the State of New York, have invented new and useful Improvements in Hermetically-Sealed Receptacles for the Preservation of Articles of Food; and I do hereby declare that the following is a full and exact description of the same.

- 10 The ordinary process of inclosing articles of food in hermetically-sealed vessels includes heating the articles to the boiling-point to expel the air, and the final sealing of the inclosure while the inclosure is at the boiling temperature. The subsequent cooling and shrinkage of inclosed substances causes a great external pressure upon the package, and renders certain the entrance of air if even the most minute orifice exists.
- 15 The object of my invention is, first, to obviate the probability of leakage by relieving the external pressure, and, secondly, in a great measure, if not entirely, to obviate the deleterious effect of a slight leakage of air. The former
- 20 I accomplish by admitting fluid to make good the shrinkage as the contents cool, and the latter is obviated by utilizing capillary attraction to carry the fluid contents to the place of leakage in a thin film, whereby the entering air, if any, will be immediately inclosed and isolated in a fluid envelope in the form of fine bubbles or froth.
- 25
- 30

My invention therefore principally consists, first, in a controllable vent, the outlet whereof may be covered with a portion of the fluid, wherewith the vessel is filled, so that as the inclosed fluid cools and shrinks other fluid will be drawn through said vent, and thus prevent a partial vacuum and the consequent external pressure.

Other improvements relating to structure will be pointed out hereinafter.

That others may fully understand my invention, I will more particularly describe it, having reference to the accompanying drawings, in which—

Figure 1 is a perspective view of a preserving-jar fitted with my invention. Fig. 2 is a vertical section of the same. Figs. 3 and 4 represent modifications.

The receptacle is in the drawings represent-

ed by the jar G, provided with a neck having a screw-thread on its outer surface to engage with a similar screw on the inner surface of the cap, A, which binds the stopple to close the jar.

It will be understood that a receptacle of any other form or of any suitable material may be employed, and that any suitable clamping or binding device may be employed instead of a screw-thread.

The orifice or mouth of the jar is occupied by a plug or stopple, D, which is fitted loosely within said mouth, but yet so closely as to leave a very thin space, d, all around between the surface of said stopple and the inner surface of the mouth of the jar. This thin space is a capillary space, and by capillary attraction it will be filled to its utmost limit with the fluid contained in the jar, if the same shall reach high enough to immerse the lower end of the plug D. The plug D may be made of any desirable or proper material, but I have found "white wood," deprived of its soluble flavoring constituents, to be entirely satisfactory. To prevent soakage of the wood by its exposed end grain, I cover it with a wafer or coating of celluloid, F, which is impervious and will not impart flavor to the fluids in contact.

A packing-disk, C, rests upon the upper edge of the neck G, and upon the upper side of the stopple D. This packing-disk may be made of any proper material, and rubber answers a good purpose.

The stopple D is made concave on top, in the center, as at e, and the cap A may conform thereto and constitute a cup to hold a little of the fluid from the jar.

A vent is made through the packing C, and an oblique hole, H, extends from said vent laterally through the stopple and opens in the concavity or depression at the center of the cap.

To increase the capillary effect the interior surface of the neck is roughened, as shown in Fig. 2 at r, and this roughened surface may be utilized to a good effect when a simple cork is used, as in Fig. 3, because said roughness will aid and increase the capillary effect, and enable the liquid to climb to the base of the cork, as it would not do if the surface were smooth and glazed. The presence of some suitable fibrous substance to form a capillary connec-

tion between the stopple and the fluids within the jar, as shown in Fig. 4, will be of advantage when glazed or vitreous stopples are employed.

The operation is as follows: The substances to be preserved are placed within the receptacle G, and being heated to the required temperature, the stopper D is put in position with the packing, and the whole forced together by the clamp. When cooling has commenced the pressure of the clamp is relaxed slightly, and the atmospheric pressure will then force some of the liquid in the concavity of the cap inward through the vent I and H under the packing to supply the shrinkage of the cooling liquid, so that when it has ceased to shrink the interior space will still be filled with liquid and external pressure will be relieved. The cap is then screwed down again, and the vent thereby closed. The capillary space between the neck and the stopple will be kept filled with liquid by the capillary attraction of the proximate walls, so that if from any defect in the closure of said neck air shall gain access to the interior space it will be immediately immersed in the capillary fluid, and isolated in the form of minute bubbles. This effect may be greatly assisted by the roughening of the interior surface of the neck of the receptacle G, whereby the fluid is enabled more readily to cling to and clinch the sides.

Having described my invention, what I claim as new is—

1. A vessel adapted to contain and preserve articles of food in a wet state, provided with a neck made rough or granular on its inner surface, and a sunken or recessed seat or shoulder, in combination with a stopple supported or confined on said seat without covering said granular surface, substantially as set forth. 35

2. A vessel or receptacle adapted to contain 40 and preserve articles of food, combined with a stopple having a concavity on its top, and a vent, I, extending from such concavity to the lower surface of the packing-disk, so that the shrinkage on cooling will be made good by the 45 entrance of similar liquid from the concavity on top of the stopple.

3. A vessel or receptacle adapted to contain or preserve articles of food in a wet state, provided with a neck roughened on its inner surface to increase capillary action, combined with a stopple loosely fitted to said neck, as set forth, whereby a capillary space is formed between 50 said neck and stopple, as set forth.

WILLIAM W. STEWART.
